UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

TOE-BINDING APPARATUS.

1,109,660.

Specification of Letters Patent.

Patented Sept. 8, 1914.

Application filed July 14, 1910. Serial No. 571,941.

To all whom it may concern:

Be it known that I, MATTHIAS BROCK, a citizen of the United States, residing at Boston, in the county of Suffolk and State of Massachusetts, have invented certain Improvements in Toe-Binding Apparatus, of which the following description, in connection with the accompanying drawings, is a specification, like reference characters on the drawings indicating like parts in the several figures.

This invention relates to machines for use in manufacturing boots and shoes and particularly to mechanism for lasting the toe portions of shoes and securing the upper in lasted position.

An object of this invention is to provide apparatus by which a binder may be applied in position for securing the toe portion of a shoe.

The apparatus is preferably combined with a toe lasting mechanism by which the shoe is supported and the upper held for the application of the fastening. The present practice is to fasten one end of a binder strand, lead the strand around the toe end of the shoe and then pull upon the strand. This procedure by which tension is applied at one end only does not tighten the binder as uniformly throughout its length as is desirable and it is comparatively slow. Another practice is to use a binder having a prong on each end. This binder is placed manually and is not tensioned at all.

An important feature of this invention consists in a binder holder adapted to receive a binder and for actuation to carry the binder into toe binding position. Preferably the holder is movable from a receiving position in which the binder may easily be placed therein into a delivering position.

In accordance with a further feature of this invention the binder holder is constructed and arranged to tighten the binder about the work after it has been placed. Also preferably provision is made for automatically disengaging the binder from the holder at the proper time.

These and other features of this invention will appear in connection with the following description and then be pointed out in the claims.

Figure 1 is a perspective view of a toe

lasting mechanism equipped with this invention. Fig. 2 is a side view showing in full and dotted lines the wiring head in its operative and its elevated, inoperative position. Figs. 3 and 4 are perspective details.

The toe lasting mechanism may comprise in addition to the toe rest 2, the wipers 4 which are caused, by motion communicated from the lever 5, to have an advancing and inward closing sweep to wipe the upper into lasted position over the feather 6 and against the lip 8 of the innersole. This type of lasting mechanism is well known and needs no further description but details thereof may be learned if desired from United States Patent No. 552,834.

To the wiper carrying head 10 there is pivoted the arms 12 of the wiring head, one arm being extended forwardly beyond its pivot to carry the counterbalance 13 which will hold the wiring head in the dotted line position Fig. 2 when the head has been raised. The rear ends of the arms which are adjacent to the shoe are connected by the cross bar 14, which is adapted to extend transversely across the shoe when the wiring head is brought into use after the upper has first been worked into lasted position and prepared for fastening. Extending forwardly from the cross bar is the toe arm 15 which has a pin and slot connection with the cross bar to permit of endwise and limited lateral movement and is pressed forwardly by a spring 16.

On the lower side of the end of the toe arm is an abutment 18 about which the middle portion of the binder 20 is engaged. This abutment is shown as of substantial length and curved to place the binder about the toe end of shoes varying in width or in pointedness of the toes. The abutment has a binder retaining construction shown as a groove 22 in its front face and a downwardly and backwardly beveled face extending in its lower edge as best shown in Fig. 3. The toe arm also carries a sliding plunger 24 sustained by a light spring and working in a guideway that intersects the groove 22. This plunger is adapted for actuation to dislodge the binder from the abutment and press it downwardly toward the upper that is to be held. The cross bar 14 has at each side of the ma-

chine a rearwardly extending arm 28 upon which is pivoted a block 29 having a slide-way extending transversely of the machine for a lever 30. The lever has on its inner 5 end a binder engaging member in the form of a depending stud 32 which is recessed on its rear side as shown best in Fig. 4 to provide a tack aperture in front of the strand or within the eye of the binder. The recess 10 may advantageously be formed open on its rear side and adapted to allow a tack to be driven as in Fig. 4 by hand or otherwise with its shank inside the binder eye and its head in position to be hit with a hammer or 15 other driver, and to carry the binder eye downwardly on the stud as the overlying tack head is driven outwardly. The outer arms of the levers 30 are connected by springs 35 to the side bars 12 to hold under 20 tension the bowed binder which extends from one stud 32 around the abutment 18 to the stud on the other side of the machine. For adjusting the levers in their slideways to position them for the width of the shoe 25 each arm 28 is pivoted to the bar 14 and the arms are connected by toggle arms 36 which are crossed and the connecting pin for which is guided in a slot in the bar arm 15. This connecting pin extends into a slot in an 30 operating lever 37 which is fulcrumed at 38. This arrangement enables the operator to move both levers 30 together for a wide or a narrow shoe. The levers can also slide independently in the blocks 29 for unsymmetrical shoes. These connections and the 35 fulcrum connection at 38 are provided with suitable friction to avoid loose or unpremeditated movement. A handled lever 40 is operatively connected with the levers 30 to 40 move them in the direction to tighten the binder about the shoe. As shown, the lever comprises a bell crank fulcrumed on the lower side of the bar 14 and acting through a segment toothed connection with a second 45 lever or vibratory arm, the lever 40 and arm being connected by links with the levers 30. Slots in the links allow free movement of the levers 30 by their springs 35. The lever 40 may carry a pawl or may have weight 50 enough at its handle end to maintain itself in adjusted position with the binder under tension, or may be otherwise made for this purpose, and will automatically return to its starting position by its own weight when 55 the wiring head is turned up into its wire receiving position as shown in dotted lines in Fig. 2. For facilitating the use of wire in which no eyes or loops have been formed the wiring head may have a spring clip 42 60 as indicated in Fig. 1 located at one or both sides of the shoe to hold the bowed wire while it is being carried into place around the toe of the shoe by the wiring head.

In the use of the invention the lasting of 65 the shoe is effected as is customary and after

the overworked upper has been suitably formed over the feather of the innersole and pressed into the angle between the lip and the feather to form a seat for the binder the usual downward molding pressure on the wipers is relaxed and they are backed away from the upstanding edge portion of the upper to present a narrow binder receiving channel between the upper and the edge of the wiper. A binder is now, or it may previously have been, placed in the binder carrying head, which with its associate parts constitutes the binder holder of the illustrated embodiment of this invention, to extend in a bowed form from the holder 32 on 70 one side of the shoe around the toe abutment to the other holder on the other side of the shoe. If the binder is provided with eyes on its ends as is preferred these eyes are merely impaled on the holders. The 75 springs 35 serve to maintain the binder taut. The head is then turned down from the dotted line binder receiving position Fig. 2 to the full line position, whereby the binder is placed about the toe of the shoe. 80

The plunger 24 may move freely enough to be actuated downwardly to force the binder automatically from its groove in the toe abutment by its weight as the head is turned down, or it may be engaged by the 85 operator for that purpose. The levers 30 then tighten the binder into binding relation to the upper to secure the upstanding portion thereof in the angle between the feather and lip of the innersole where it has 90 been molded by the wipers. The wipers are preferably now advanced to drive the binder in front of them snugly into the angle and hold it in binding position until the ends are anchored. If greater tightening force 95 is desired than that exerted by the springs 35 it can be obtained by the use of the hand lever 40 which is retained in adjusted position by friction. The tacks are then driven 100 through the eyes of the binder in the holders 32, the eyes being forced down by the heads of the tacks by the hammer in driving the tacks. The binder carrying head may then 105 be turned upward to its binder receiving position where it is maintained by its counterweight 13, the lever arm 40 being automatically returned to its forward position by its weight as the head is turned up. The head is now ready to receive another binder 110 115 for fastening the next shoe. While it is preferred to employ binders having eyes which may have been previously formed in the course of their manufacture, a strand of binding material with an eye in one end only can be advantageously employed and 120 the binder tensioned by force applied to the strand end, that is, the left hand end, after the adjacent tack is driven and preparatory 125 to wrapping the wire around the tack and severing it from the strand. Also a binder 130

strand without eyes may be employed if desired, the binder ends being held by a spring clip at each side of the head.

Having explained the nature of this invention and described a preferred construction embodying the same, I claim as new and desire to secure by Letters Patent of the United States:—

1. In a machine of the class described, a binder holder mounted for movement at an angle to the plane of the shoe bottom from a position to receive a toe binder into position to deliver the binder to a shoe.
2. In a machine of the class described, toe lasting mechanism, a binder holder adapted to receive a toe binder that is unattached to the shoe while the holder is in a position remote from the work and which is movable independently of the toe lasting mechanism to deliver the binder in a position in which it embraces the toe portion of the shoe.
3. In a machine of the class described, the combination with end embracing wipers, of a binder holder movable from binder receiving position above the plane of the wipers into position to deliver the binder in front of the wipers.
4. In a machine of the class described, the combination with end embracing wipers, and means for actuating the wipers to work an upper into lasted position over the feather of an innersole and then to back away from the edge portion of the upper to permit the application of a toe binder, of a binder holder movable to apply a binder to the shoe in the channel between the edge portion of the upper and said wipers.
5. In a machine of the class described, the combination with end embracing wipers, and means for actuating the wipers to work an upper into lasted position over the feather of an innersole and then to back away from the edge portion of the upper to permit the application of a toe binder, of a binder holder movable downwardly into the channel between the edge of the upper and said wipers to deliver a bowed binder in said channel.
6. In a machine of the class described, a binder holder pivotally mounted in front of a shoe and adapted for movement from an upright, binder receiving position downwardly into a substantially horizontal position for placing the binder upon the marginal portion of the shoe bottom.
7. In a machine of the class described, a toe binder holder comprising supports for the end portions of the binder and a separate support for the middle portion of the binder.
8. In a machine of the class described, a toe binder holder comprising a curved abutment about which the middle portion of the binder is held, and end supports.
9. In a machine of the class described, a

toe binder holder comprising a curved abutment about which the middle portion of the binder is held and rearwardly acting end supports adapted to hold the upper under tension about the curved abutment.

10. In a machine of the class described, a toe binder holder comprising a curved central abutment and means for forming the binder around said abutment as an inside shaping member.

11. In a machine of the class described, a toe binder holder comprising a curved central abutment 18 and the swinging end supports 30 having the springs 35 for moving the end supports in the direction to hold the binder taut about the abutment.

12. In a machine of the class described, a toe binder holder comprising an abutment for the binder and means for pressing the binder downwardly from the abutment toward upper holding position.

13. In a machine of the class described, a toe binder holder comprising a toe abutment for the binder having an inclined lower outer edge face, supports for the end portions of the binder, means for pressing the binder downwardly on the toe abutment to dislodge it therefrom, and means acting through said end supports for tightening the binder as it is so pressed from the abutment.

14. In a machine of the class described, lasting instrumentalities, and a holder adapted to receive a toe binder and movable separately from the lasting instrumentalities to present the binder in bowed form in position to be secured to the toe portion of a shoe.

15. In a machine of the class described, the combination with toe lasting devices, of means for applying a toe binder to the lasted shoe from above the shoe and operating to insert the binder between the inner edge of the lasting devices and the toe stock which is to be bound by it.

16. In a machine of the class described, the combination with toe lasting devices, of means for applying a toe binder to the lasted shoe from above the shoe, said means being constructed and arranged to present the binder in bowed form to fit substantially the toe portion of the shoe.

17. In a machine of the class described, the combination with toe lasting devices, of means having a position above the shoe and movable therefrom toward the shoe bottom for applying a toe binder to the lasted shoe from above the shoe, said means being constructed and arranged to place under tension the binder between the lasting devices and the stock to be bound.

18. In a machine of the class described, the combination with toe lasting devices, of means for applying a toe binder to the lasted shoe from above the shoe, including

- manually operated means to tension the binder about the stock to be bound.
19. In a machine of the class described, toe lasting means and a holder separate from 5 said means and adapted to receive a toe binder, said holder being constructed and arranged to support simultaneously the two end portions of the binder and movable to present the binder in bowed form in position 10 to be secured to the toe portion of a shoe and hold the binder in position to be anchored at its two ends to the shoe.
20. In a machine of the class described, lasting instrumentalities, and a holder adapted 15 to receive a toe binder and movable separately from the lasting instrumentalities to present the binder in bowed form in position to be secured to the toe portion of a shoe, said holder having capacity for self 20 adjustment to adapt it for use on shoes of different shapes and sizes.
21. In a machine of the class described, a holder adapted to receive a toe binder in 25 bowed form and including a support for the middle portion of the binder and separately yielding supports for the end portions of the binder.
22. In a machine of the class described, a holder adapted to receive a toe binder in 30 bowed form and including a support for the middle portion of the binder and end supports which are movable transversely of the shoe to adapt themselves to the width of the shoe and are yieldingly actuated lengthwise 35 of the shoe.
23. In a machine of the class described, a toe binder holder comprising a toe abutment for the binder and end supports therefor which are mounted for movement transversely and longitudinally of the shoe.
24. In a machine of the class described, a toe binder holder comprising a toe abutment 30 for the binder and end supports therefor which can slide toward and from each other 45 and are pivotally mounted to swing lengthwise of the shoe, and actuating means for the end supports.
25. In a machine of the class described, a toe binder holder comprising a toe abutment 50 having a groove for the binder and forwardly yielding end supports to hold the binder in said groove.
26. In a machine of the class described, a toe binder holder comprising a toe abutment 55 having a groove for the binder, means to dislodge the binder from the groove, and forwardly yielding end supports acting to draw the binder against the toe portion of the upper when it is dislodged from the 60 abutment.
27. In a machine of the class described, a toe binder holder mounted for movement from a binder receiving position to a binder delivering position, and means for automati- 65 cally dislodging the binder from a member of the holder when the holder reaches the delivering position.
28. In a machine of the class described, a toe binder holder mounted for movement from a binder receiving position to a binder 70 delivering position and comprising toe and yielding end supports for the binder and means for dislodging the binder from the toe support while the holder is in delivering position and permitting the yielding end supports to draw the binder into holding relation to the shoe upper.
29. In a machine of the class described, a binder holder having a binder end support 75 constructed and arranged to be embraced by an eye on a binder end and to permit a tack to be driven in anchoring relation thereto and open on its rear side to permit the passage of an upstanding portion of the tack during relative movement of the shoe and 80 holder.
30. In a machine of the class described, a binder holder having a binder end support 85 presenting a downwardly extending member to receive an eye in the binder end and having a recess through which an anchor tack for the binder may be driven within 90 said eye.
31. In a machine of the class described, a binder holder having a binder end support 95 presenting a downwardly extending member to receive an eye in the binder end and having a recess open at its rear side to permit an anchor tack to be driven in close proximity to the rear portion of the eye 100 with the head of the tack overlying the binder whereby the eye may be forced downwardly on said member by the ingoing tack.
32. In a machine of the class described a toe binder holder having an abutment for 105 the middle portion of the binder which is mounted to yield lengthwise of the shoe.
33. In a machine of the class described a toe binder holder having an abutment for the middle portion of the binder which is 110 mounted for limited lateral positioning movement.
34. In a machine of the class described a toe binder holder having at one side a binder eye support formed to permit the insertion 115 of an anchor tack in the binder eye and having at the other side a spring clip to retain the binder in position to be tightened.
35. In a machine of the class described a toe binder holder having at one side a binder 120 eye support formed to permit the insertion of an anchor tack in the binder eye and having at the other side a member formed to position the binder and facilitate the driving of an anchor tack adjacent thereto, and a binder strand retainer for the purpose described.
36. In a machine of the class described a 125

- toe binder holder arranged to tip from a binder receiving position to a delivering position and balanced to remain in the former position when moved thereto.
- 5 37. In a machine of the class described means to form a seat for a toe binder and for pressing the binder into its seat and means for placing the binder in said seat between the seat forming and the pressing 10 operations.
38. In a machine of the class described means to form a seat for a toe binder, means for placing the binder in said seat, and means constructed and arranged for operation to tighten the binder after it has been so placed.
39. In a machine of the class described, means for placing a binder about the toe portion of a lasted shoe by movement in 15 one direction and operating means to effect tightening of the binder by movement of its ends in a different direction from the binder placing movement.
40. In a machine of the class described, 20 means for placing a binder about the toe portion of a lasted shoe including means operative after the binder has been so placed for tightening the binder into binding relation to the shoe.
- 30 41. In a machine of the class described, means for placing a toe binder about a shoe and means connected with opposite ends of the binder to tension it and hold it in position to be fastened.
- 35 42. In a machine of the class described a binder holder movable to place a toe binder about the end portion of a shoe combined with means to press the binder into binding relation to the upper.
- 40 43. In a machine of the class described a binder holder mounted to have a downward and rearward movement relatively to the shoe for placing a bowed toe binder about the toe end of the shoe.
- 45 44. In a machine of the class described a binder holder mounted to have a downward and rearward movement relatively to the shoe for placing a bowed toe binder about the toe end of the shoe combined with means for tightening the binder rearwardly after 50 it has been so placed.
45. In a machine of the class described a binder holder mounted to have a downward and rearward movement relatively to the shoe for placing a bowed toe binder about 55 the toe end of the shoe combined with means acting at the outer side of said bowed binder to press it farther rearwardly for seating it and the upper in front of it into the angle between the feather and lip of the innersole. 60
46. In a machine of the class described toe binder tightening means arranged to move into and out of operative relation to the shoe and including an actuator with provision for maintaining the actuator in 65 adjusted position and arranged to retract the actuator automatically when the binder tightening means is returned to its inoperative position.
47. In a machine of the class described toe 70 binder tightening means including the pivotally mounted support 12, 14, the levers 30, and the actuator 40 movable in a horizontal plane and arranged to maintain its adjusted position while the tightening means is operative and to swing back automatically by its own weight when the support is turned upwardly.
48. In a machine of the class described the combination with toe lasting mechanism, 80 of a binder holder movable downwardly from a position over the shoe to apply to the toe portion of the shoe a binder for retaining the upper in lasted position.
49. In a machine of the class described, 85 the combination with end embracing wipers, of a binder holder movable from binder receiving position out of the plane of the wiper into position to deliver the binder into the plane of the wipers and in front of 90 the wipers.
- In testimony whereof I have signed my name to this specification in the presence of two subscribing witnesses.
